C. W. King.

Inventor,

UNITED STATES PATENT OFFICE.

CHARLES W. KING, OF WILLIAMSTON, MICHIGAN.

WRITING-FRAME.

SPECIFICATION forming part of Letters Patent No. 391,747, dated October 23, 1888.

Application filed July 30, 1888. Serial No. 281,378. (No model.)

To all whom it may concern:

Be it known that I, CHARLES W. KING, a citizen of the United States, residing at Williamston, in the county of Ingham and State of Michigan, have invented a new and useful Improvement in Writing-Frames, of which the following is a specification.

The object of my invention is to provide a writing-frame to enable the blind to write by providing means to preserve the alignment of the letters; and I attain this object by the novel construction and combination of devices, fully described hereinafter in connection with the accompanying drawings, and specifically 15 pointed out in the appended claims.

In the drawings, Figure 1 is a perspective view of a writing-frame embodying my invention. Fig. 2 is a longitudinal central sectional view. Fig. 3 is a detail horizontal sectional view.

Referring by letter to the drawings, A designates the base-plate of the writing-frame, which is provided at one side with the grooved flange B and at the other side with the plain flange B', and C designates a sliding frame, which bears on the said plate between the said flanges, and is engaged at the edge adjacent to the flange B in the groove therein.

The space-bar D, which is arranged on the 30 side of the sliding frame adjacent to the flange B', is provided with a series of notches or grooves, d d, arranged at the same intervals as the lines on ordinary writing-paper, and E represents an engaging-spring, which is affixed to the side of the base-plate, and is provided on its free end with a stud, e, adapted to engage the said notches or grooves, whereby the sliding frame may be locked in any desired 35 position.

40 F represent similar barrels or tubes, which are arranged near the opposite sides of the sliding frame, and they are provided in their adjacent sides with registering grooves f f, of about the same length as the lower loops of such letters as g f q y, &c. In these grooves 45 are arranged the opposite ends of the yielding base-line rod G, and the ends of this rod are normally held in the upper ends of the said slots by the contractile springs H H, which are located in the barrels or tubes.

K represents a paper-holder, arranged at the upper end of the base-plate; and it consists of a clamping-bar hinged to the said base-plate and provided with an actuating-spring, k, to normally hold its lower side pressed 55 against the upper side of the base-plate. The under side of this clamping-bar is provided with the depending points k' k', which are adapted to engage a sheet of paper when inserted under the clamping-bar.

60 The operation of the device is as follows: Remove the sliding frame and place a sheet of writing-paper on the base-plate, engaging its upper edge under the spring-actuated clamping-bar; engage the free end of the spring E 65 in the notch or groove at the lower end of the space-bar, and the device is in condition for use. The pencil or pen is now used in the ordinary way, the yielding rod serving as a base-line, above which all the letters which are intended to be above the line are formed, and when a loop is formed which extends below the base-line the pencil or pen is pressed downward upon the said rod and it will yield freely. When the pressure upon the base-line rod is removed, it will resume its normal 70 position. When the end of one line is reached, the sliding frame is moved down one space, and the spring E is engaged in the next notch or groove d, as will be readily understood.

75 The invention is simple, easily operated, readily understood, and will effectually accomplish the desired purpose in enabling the blind to write correctly and rapidly without forming the letters out of the true alignment.

80 Having described the invention, I claim—

1. A writing-frame comprising a base-plate, a sliding frame mounted on the base-plate, and a yielding base-line rod carried by said sliding frame, as set forth.

90 2. A writing-frame comprising a base-plate, a sliding frame mounted on said base-plate, a base-line rod carried by said sliding frame, and coiled springs having their ends secured to the said rod and the frame, whereby the 95 said rod is permitted to yield to the pen when the extended letters are being formed, as set forth.

100 3. In a writing-frame, the combination of the base-plate provided at its opposite sides with

the vertical flanges B and B', the said flange B being provided with a groove, the sliding frame arranged on the base-plate between the flanges and engaging at one edge in the groove 5 in the flange B, the space-bar on the opposite side of the sliding frame, the spring E, attached to the base-plate and bearing on the space-bar, and the base-line rod mounted on the sliding frame, substantially as specified.

10 4. In a writing-frame, the combination, with the sliding frame, of the barrels or tubes arranged thereon and provided with registering

slots *ff*, the base-line rod mounted at its ends in the said slots, and the contractile springs located in the barrels or tubes and connected to the ends of the said rod, substantially as specified. 15

In testimony that I claim the foregoing as my own I have hereto affixed my signature in presence of two witnesses.

CHARLES W. KING.
